UNITED STATES PATENT OFFICE.

HARRY A. KUHN, OF PITTSBURG, PENNSYLVANIA.

METHOD OF MINING COAL.

970,725.

Specification of Letters Patent. Patented Sept. 20, 1910.

Application filed October 19, 1907. Serial No. 398,196.

To all whom it may concern:

Be it known that I, HARRY A. KUHN, a resident of Pittsburg, in the county of Allegheny and State of Pennsylvania, have 5 invented a new and useful Improvement in Methods of Mining Coal; and I do hereby declare the following to be a full, clear, and exact description thereof.

My invention relates to a method of mining coal or like substances.

In the method heretofore generally employed in mining coal it has been customary to make an undercut in the wall of coal adjacent to the bottom of the mine, and then 15 holes were drilled in the body of coal above the undercut into which blasts of powder or dynamite were inserted. The effect of the blast was to break down the coal and great quantities of it were often reduced 20 to a very fine state so as to be practically useless for certain purposes, thereby greatly reducing the value of the output of the mine. It is very difficult for the miner to judge the effect that a certain charge of 25 powder will have on the coal in all cases, as the effect may vary according to the seam in which the work is being done, so that the blasting has always been done more or less in a haphazard sort of manner.

30 The object of my invention is to provide a method of mining coal which will dispense with the blasting and which will produce the coal in large lumps, thereby doing away with the fine slack which has to be 35 disposed of at a very low price.

To these ends my invention comprises, generally stated, the method of mining coal consisting in making a plurality of parallel cuts simultaneously in the wall or solid of 40 the coal seam, and subdividing intermittently the direct cutting force, making each cut, into two component forces, one component working in the plane of the cut and the other component working at an angle to the 45 plane of the cut, thereby cutting and directing simultaneously all the coal in a definite direction to a definite place and then conveying away the coal from said place.

In the accompanying drawing Figure 1 is 50 a side elevation partly in vertical section of a suitable machine for carrying out my invention; Fig. 2 is a plan view; Fig. 3 is an enlarged section on the line 3—3 Fig. 1; Fig. 4 is an enlarged detail of the yoke 55 head; Fig. 5 is an inverted view of one of

the disk cutters; Fig. 6 is an enlarged detail of a portion of a cutter and wedge; and Fig. 7 is a face view of the wall of coal after the cuts have been made therein.

I will describe my improved method in 60 connection with a suitable machine, although my improved method may be carried out with varied forms of apparatus.

In the drawing the numeral 2 designates a suitable truck with the wheels 3 adapted 65 to travel on the track 4 which is laid in the mine. Erected on the truck 2 is the frame 5 which may be composed of channels and angle bars suitably connected and braced to form a rigid structure. Supported by the 70 frame is the conveyer trough 6 which is arranged at an incline and within said trough is the conveyer chain 7 provided with the conveyer arms 8. This chain passes around the sprocket wheels 9 and 10 at the rear end 75 of the machine, said sprockets being mounted on the shafts 11 and 12, respectively. A motor 14 is mounted on the truck 2, and the motor shaft has the pinion 15 thereon which meshes with the pinion 16 which 80 meshes with the pinion 17 on the shaft 18. This shaft 18 carries the bevel pinion 19 which meshes with the bevel pinion 20 on the shaft 11. The chain 8 passes around the sprocket wheel 21 on the vertical shaft 85 22. Secured to the lower end of the shaft 22 is the under-cutter disk 23. Carried by the truck 2 is the carriage 24 mounted on the wheels 25. On said carriage 24 is the frame 26 which has the center pin 27 swiv- 90 eled in the center plate 28 of the carriage 24. This frame 26 has the uprights 29 connected at the upper end by the channels 30. Within the uprights 29 are the vertical 95 guide-ways 31.

Resting on the frame 26 is the base plate 32 provided with the upright end pieces 33 which have the tongues 34 engaging the grooves 31 in the standards 29. To provide for the raising and lowering of the base plate 32 threaded bars 35 engage threaded seats 36 in the end blocks 33. The upper ends of the threaded bars 35 are held against longitudinal movement in bearings 37 on the frame 26. At the upper ends of the entire threaded standards 35 are the bevel pinions 38 which are engaged by bevel pinions 39 on the shaft 40. On the outer end of the shaft 40 is the sprocket 41 which is connected up by the chain 42 to the sprocket 43 on 105 110

the stub shaft 44. Secured to the stub shaft 44 is the operating wheel 45.

Mounted on the base plate 32 is the motor 46 and a pinion 47 on the motor shaft engages 5 the gear wheel 48 on the shaft 49. The shaft 49 projects through the forward end block 33 and through the gear wheel 50 which is bolted to the yoke 51 by the bolts 52. This gear wheel 50 has the recessed 10 portion 53 which is adapted to engage the inwardly projecting portion 54 of the end block 33. This permits of the rotary movement of the gear wheel 50 for the purpose hereinafter set forth. The pinion 55 meshes 15 with the gear wheel 50, said pinion being mounted on the shaft 56 operated by the handle 57.

The shaft 49 passes through the yoke 51 and carries at its outer end the pinion 58 20 which meshes with the pinion 59 on the shaft 60 journaled in the yoke 51. Mounted on the shaft 60 are the sprockets 61 and 62. Sprocket chains 63 lead from the sprockets 61 and 62 to the sprocket wheels 25 64 on the shaft 22^a. Idler sprockets 65 are mounted on the shaft 66 to guide the sprocket chains 63. The chains 63 are provided with the conveyer arms 68 which are adapted to sweep over the cuts made by the 30 disk cutters 69 and convey the dust or cuttings from said cuts. These disk cutters 69 are secured to the shaft 22^a and said shaft is driven by the sprocket chains 63. Secured to the lower face of the disk cutters 35 69 are the wedges 70 which are adapted to wedge down the coal in the manner herein-after set forth.

In order to provide for the driving of the undercutter 23 a clutch sleeve 71 is secured 40 to the sprocket 72 which is mounted on a suitable shaft on the bracket 73 extending out from the truck 2. This clutch is adapted to engage a clutch face on the lower sprocket 62. A sprocket chain 74 is adapted to pass 45 around the sprocket 72 and around the sprocket wheel 75 on the shaft 22 to which the undercutter 23 is secured.

In carrying out my improved method with the above described apparatus, the 50 truck is run into the mine upon the track 4, and when the cutters have been brought up in front of the face or seam of the coal power is applied to drive the cutters, where-upon the cutters rotating at a high rate of 55 speed cut into the face of the coal and a plurality of parallel cuts or kerfs are made therein, leaving between the cuts the partially severed block of coal. Simultaneously with the cutting of these parallel cuts 60 the action of the wedges 70 takes place which, rotating as they do with the cutting disks, bring a force to bear upon the partially severed blocks at an angle to the line of the cut, whereby the said blocks are 65 broken by said force and the coal in this way

dislodged. In other words, I subdivide intermittently the direct cutting force, making each cut and working in each cut, into two component forces, one component force working in the plane of the cut and acting 70 to cut the coal and the other component force working at an angle to the plane of the cut, which is the wedging action, whereby the coal is cut and dislodged simultaneously and when so dislodged is directed in a 75 definite direction to a definite place to be acted on by the conveyer arms 8 and conveyed away.

The carriage carrying the cutters may be conveyed in any suitable manner, and after 80 a series of cuts have been made to proper depth and the coal between the cuts dislodged, the carriage may be withdrawn, whereupon the operator by turning the hand wheel 45 and through the threaded 85 bars 35 lifts or raises the bed plate 32 carrying the motor and the parts connected therewith, together with the yoke carrying the cutters 69. This lifting of the bed plate may be continued until the cutters 69 have 90 been brought into the position shown in dotted lines in Fig. 1, whereupon power is applied to rotate said cutters and another series of parallel cuts are made at a higher 95 point. In the same manner as above described this coal at a higher level is cut and dislodged. By raising the bed plate 32 the sprocket 62 is disconnected from the clutch 71 and the under-cutter 23 remains inoperative. 100

If desired, a plurality of vertical cuts may be formed in the coal and to accomplish this the operator turns the handle 57 and so rotates the yoke 51 until the disk cutters 69 are brought around into a vertical position. 105

By the above method I am enabled to remove the coal continuously by making a series of parallel cuts and dislodging the coal between the cuts without cutting, clawing or scraping it loose. In connection with the cutting operation I combine a force which acts at an angle to the line of cut and which breaks loose the coal in lumps and with great saving in power. Furthermore, the coal as it is cut is continuously directed to one spot where the conveyer receives it and conveys it away to be loaded upon the cars. 115

After having made a series of horizontal parallel cuts in the face of the coal I may stop the operation of the machine before the wedges have begun to break loose the coal and by swinging the machine around so as to bring the cutters into the vertical position indicated in dotted lines Fig. 1, I may make 120 a series of cross cuts intersecting the parallel cuts. In this manner I cross-cut the face of the coal at regular intervals so that the coal is readily broken down by means of the wedges when the cutters penetrate suffi- 125 130

ciently to bring these wedges or jars to bear, the coal when cross-cut in the above manner breaking off in large lumps and the amount of fine slack is reduced. Furthermore, by 5 cross-cutting in this manner and by cutting down the coal the face of the coal is kept apparently even so that when the next cutting operation begins I have a comparatively even wall to work on.

10. My improved method may be carried out by other forms of apparatus than that illustrated and described, such as by two cutters operated as saws with means carried thereby for dislodging or breaking loose the coal between the cuts by means of a tool consisting of two cutters connected up to a common shank portion adapted to be driven into the wall of the coal by blows administered to the shank portion and a wedge carried by one 15 of the cutters adapted to dislodge or break loose the coal severed by the cutters.

What I claim is:

1. The method of mining coal consisting in cutting a plurality of slits simultaneously in the wall or solid of the coal at right 25 angles to the face thereof, and dislodging the coal lying between said slits simultaneously with the cutting action.

2. The method of mining coal, consisting 30 in cutting a plurality of parallel slits simultaneously in the wall or solid of the coal at right angles to the face thereof, and dis-

lodging the coal lying between said slits simultaneously with the cutting action.

3. The method of mining coal, consisting 35 in cutting continuously a plurality of slits simultaneously in the wall or solid of the coal, and applying a dislodging force intermittently in the slits at an angle to the plane of the cut, while the cutting operation is 40 going on.

4. The method of mining coal, consisting in cutting a plurality of slits at the same time in the wall or solid of the coal, and subdividing intermittently the direct cutting 45 force making each cut and working in each cut into two component forces, one component force working in the plane of the cut and the other component force working at an angle to the plane of the cut, whereby the 50 coal is dislodged.

5. The method of cutting coal, consisting in cutting a plurality of parallel cuts in the wall or solid of the coal, then making a series of cross cuts intersecting said first cuts, and 55 breaking loose the coal between said cuts simultaneously with the cross cutting action.

In testimony whereof, I the said HARRY A. KUHN have hereunto set my hand.

HARRY A. KUHN.
